Des. 216,044
Patented Nov. 18, 1969

216,044

ICE CREAM MERCHANTISER

Walter E. Moore, Bel-Nor, Mo., assignor to UMC Industries, Inc., St. Louis, Mo., a corporation of Delaware

Filed June 20, 1968, Ser. No. 12,453

Term of patent 7 years

Int. Cl. D20—01

U.S. Cl. D52—3

FIG. 3

FIG. 1

FIG. 2

FIG. 4

FIG. 1 is a front elevation of an ice cream merchandiser, showing my new design;

FIG. 2 is a right side elevation of FIG. 1;

FIG. 3 is a top plan view; and

FIG. 4 is a perspective view of the merchandiser, showing its left side.

The rear of the ice cream merchandiser is substantially flat and plain in appearance.

I claim:

The ornamental design for an ice cream merchandiser, substantially as shown and described.
